TRUNK

Filed Sept. 7, 1927

INVENTOR.
ROY E. HARRIS

BY

A. B. Bowman,
ATTORNEY

UNITED STATES PATENT OFFICE

ROY E. HARRIS, OF SAN DIEGO, CALIFORNIA

TRUNK

Application filed September 7, 1927. Serial No. 217,916.

My invention relates to travellers' trunks and the objects of my invention are: First, to provide a device of this class which may be used as either a wardrobe trunk or a 5 steamer trunk; second, to provide a device of this class in which two steamer size trunks are readily removably secured together when it is desired to use them as a wardrobe trunk; third, to provide a device 10 of this class in which the bottoms of the two steamer size trunks have interlocking means which, when secured together, are very rigid and will not separate or become jammed if roughly handled; fourth, to provide a device 15 of this class which is especially braced against diagonal strains which occur when the trunk is dropped on one corner; fifth, to provide a device of this class in which the two sections are easily and quickly 20 secured together; sixth, to provide a device of this class in which either of the two sections may be shipped or otherwise used alone; seventh, to provide a device of this class in which the interlocking means will 25 not jam under ordinary conditions; and eighth, to provide a device of this class which is durable, neat in appearance, efficient in its action, sturdy of construction, and which will not readily deteriorate or 30 get out of order.

With these and other objects in view, as will appear hereinafter, my invention consists of certain novel features of construction, combination and arrangement of parts 35 and portions as will be hereinafter described in detail and particularly set forth in the appended claims, reference being had to the accompanying drawings and to the characters of reference thereon which form a 40 part of this application, in which:

Figure 1 is a perspective view of the two trunk sections secured together; Fig. 2 is a perspective view of the two trunk sections when separated at one side; Fig. 3 is an 45 enlarged fragmentary sectional view of the interlocking cleat shown through 3-3 of Fig. 2; Fig. 4 is an enlarged fragmentary sectional view through 4-4 of Fig. 2 showing the means for interlocking the corners of the two trunk sections; Fig. 5 is a

still further enlarged fragmentary sectional view through 5-5 of Fig. 2 showing the locking means; Fig. 6 is another enlarged fragmentary sectional view through 6-6 of Fig. 2 showing the reinforced edges and 55 the means for securing them together; Fig. 7 is a fragmentary sectional view through 7-7 of Fig. 5, showing one of the locking mechanisms; and Fig. 8 is an enlarged fragmentary sectional view through 8-8 of Fig. 2 showing the means of hinging the one side of the two trunk sections.

Similar characters of reference refer to similar parts and portions throughout the several views of the drawings.

Trunk sections 1 and 2, interlocking corner reinforcing members 3 and 4, interlocking and reinforcing side edge members 5 and 6, interlocking separable hinged members 7 and 8, interlocking cleats 9 and 10, 70 casters 11, bolt casing 12, bolt actuating disc 13, lock bolt 14, bolt actuating rod 15, and actuating rod securing means 16, constitute the principal parts and portions of my trunk.

The trunk sections 1 and 2 are similar in size and shape to the conventional steamer trunk and are provided with bottoms 1^a and 2^a, respectively, which are preferably formed from heavy sheet metal. The bottom 1^a of the trunk 1 is provided with a triangular pressed out portion 1^b at each corner thereof, with the apex formed into a full rounding curve. Adjacent to each pressed out portion 1^b is a triangular slightly indented portion 1^c, the apex of which is toward the center of the trunk. Each bottom corner of the trunk 1 is provided with a corner reinforcing member 3, which is formed from suitable material and formed 75 into three substantially square portions 3^a positioned at right angles to each other, with their common point of contact rounded thus forming a corner reinforcing similar to the conventional corner reinforcing for 80 trunks. One of the square portions 3^a, however, extends over the bottom 1^a of the trunk section 1 and coincides with the pressed out portion 1^b and the extended portion 1^c. The other two square portions coincide with 85 90 95 100

the corners of the ends and sides of the trunk section 1 as shown best in Fig. 2 of the drawings. The bottom 2^a of the trunk section 2 is provided with a triangular indented portion 2^b at each corner thereof which coincides with the pressed out portion 1^b of the trunk section 1. Adjacent to the triangular indented portion 2^b is a triangular pressed out portion 2^c which coincides with the indented portion 1^c of the trunk section 1 as shown best in Figs. 2 and 4 of the drawings. Each bottom corner of the trunk section 2 is provided with a corner reinforcing 4 similar to the corner reinforcing 3, the one portion 4^a thereof coinciding with the triangular indented and pressed out portions 1^b and 1^c, respectively, and the other square portions coinciding with the corners of the ends and sides of the trunk section 2. The corner reinforcing 3 and 4 are made with full rounding edges so that they will not be smashed or jammed out of shape by rough handling.

Extending along three of the side edges between the reinforced corners of the trunk section 1 is a channel shaped ridge 5 which may be formed by placing channel irons of suitable size along the bottom edge of the trunk as shown best in Figs 2 and 6 of the drawings. The corresponding three sides of the trunk 2 are provided with a ridge portion 6 which may be formed by bending the bottom 2^a into the desired shape or by securing T irons to the side edges of the bottom 2^a. The leg of the T iron fits into the channel iron 5 of the trunk section 1. The bottom edge of the trunk section 1 is provided with binding 1^d which is shaped around the channel iron 5. Similar binding 2^d is placed along the side edges and over the ridge 6 of the trunk section 2. Thus, when the sections are separated there are no unattractive edges of metal showing, and when the sections are together the two trunk sections give the appearance of a single trunk as shown in Fig. 1 of the drawings.

The remaining bottom edge of the trunk sections 1 and 2 are adapted to be hinged together. A channel shaped member 7 is secured by its one leg to the bottom 1^a of the trunk section 1 with its face extending flush with the side of the trunk. A similar channel member 8 is secured to the bottom 2^a of the trunk 2 by its one leg with its face extending inwardly from the side of the trunk and its leg positioned adjacent to the edge of the trunk as shown in Fig. 8 of the drawings. The unsecured leg 7^a of the channel shaped member 7 fits into the channelled portion of the channel member 8. Similarly the legs 8^a of the channel member 8 fits into the channel portion of the channel member 7. Thus the two trunks are connected together on the one

side against all movement except a lateral outward movement on the trunk section 1 in relation to the trunk section 2, and a substantially pivotal movement of the two trunks in relation to each other.

The bottom 1^a of the trunk section 1 is provided with pairs of cleats 9 thereon, the one pair being near the top edge and the other pair being positioned near the lower edge of the trunk section. The cleats 9 are divided into two sections 9^a and 9^b, which are positioned in offset relation to each other. Similar cleats 10 are provided on the trunk section 2 and are separated into sections 10^a and 10^b which are positioned in offset relation to each other. These cleats 9 and 10 of the 2 trunk sections are adapted to nest together. The sections 9^a and 10^a are adapted to fit snugly side by side as shown best in Fig. 3 of the drawings, and the sections 9^b and 10^b are adapted to fit snugly end to end. Conventional ball and socket trunk castors 11 are mounted in the outer ends of each pair of cleats 9 and 10. Recess portions 1^e and 2^e are provided in the trunk sections 1 and 2, respectively, which are adapted to receive the ball portion of the castors 11, when the slots are secured together, as shown best in Fig. 3 of the drawings.

Secured adjacent to the side edge reinforcing channel iron 5 of the trunk section 1, in spaced relation, are a plurality of bolt casings 12. Revolubly mounted in the casings 12 are bolt actuating discs 13 to which is pivotally secured a lock bolt 14, which is adapted to slide through slots in the legs of the channel member 5, and through coinciding slots in the leg member of the T shaped ridge portion 6. The end of the bolt 14 is bevelled in order that the two trunk sections will be drawn together as the bolt is thrust into the channel member. A continuous actuating rod 15 extends between the lock casings 11 and is pivotally connected to each of the discs. Said actuating rod 15 is adapted to simultaneously operate the several bolts 14.

The bolt actuating rod 15 is bent near its upper extremity to clear the corner reinforcing members 3 and 4. An indented portion 1^f is formed in the bottom of the trunk section 1 which extends under the channel reinforcing 5 and forms a slot therewith. The bolt actuating rod 15 extends into the indented portion 1^f and through the top of the trunk. A depression 1^g is formed in the top of the trunk section 1 through the one end of which extends the end of the bolt actuating rod 15. Secured to the end of the rod 15 is a link member 16^a which forms a part of the trunk lock means 16. Mounted on the extended end of the link 16^a is a lock mechanism 16^b which extends into a retainer 16^c which is secured

to the trunk 1. The locking mechanism may be of any conventional style or design. The object of the locking means is merely to hold the trunks together when being shipped and is only to prevent the two trunks from working loose from one another, as each trunk section is provided with its own lid which is locked in the conventional manner.

10 Thus, to separate the trunks, the trunks are stood on end as shown in Fig. 2 of the drawing, and the lock 16 is loosened and turned to the position shown by the dotted lines in Fig. 5 of the drawings. The bolt actuating rod 15 is pulled upwardly causing the bolt portion 14 to move into the position shown by the dotted lines in Fig. 7 of the drawings. One of the trunks is pivoted on the hinge means 7 and 8 until the interlocking cleats, corner reinforcing, and side ridges disengage each other, then the hinge is separated. The trunk sections can then be used as steamer trunks. The rod 15 is then moved back to its original position and the lock 16 is closed. The two trunks are then in condition to be shipped or used separately. If it is desired all the edges may be interlocked as shown in Fig. 6, and two such locking means may be used, one 30 on either side of the trunk.

Although I have shown and described a particular construction, combination and arrangement of parts and portions, I do not wish to be limited to this particular construction, combination and arrangement, but desire to include in the scope of my invention the construction, combination and arrangement substantially as set forth in the appended claims.

40 Having thus described my invention, what I claim as new and desire to secure by Letters Patent is:

1. In a device of the class described, a trunk comprising a pair of easily separable self contained sections, including cover and bottom members interlocking reinforced ridges in the bottom edges of each of said trunk sections, interlocking cleats on said bottom members so positioned as to prevent 50 both lateral and longitudinal relative movement of said sections and castors mounted therein.

2. In a device of the class described, a trunk comprising a pair of easily separable 55 sections, separable hinge means along the one edge of their adjacent sides, interlocking ridges along the remaining edges of their adjacent sides, and interlocking cleat members extending from the adjacent sides of 60 said trunk sections.

3. In a device of the class described, a trunk comprising a pair of easily separable sections, interlocking channel members forming separable hinge means along the one 65 edge of their adjacent sides, and interlocking

ridges along the remaining edges of their adjacent sides.

4. In a device of the class described, a trunk comprising a pair of easily separable sections, separable hinge means along the one edge of their adjacent sides, interlocking ridges along the remaining edges of their adjacent sides, interlocking cleat members extending from the adjacent sides of said trunk sections, and interlocking and reinforced corners on the adjacent sides of said trunk sections. 70

5. In a device of the class described, a trunk comprising a pair of easily separable sections, separable hinge means along the one edge of their adjacent sides, interlocking ridges along the remaining edges of their adjacent sides, and interlocking, reinforced corners on the adjacent sides of said trunk sections. 75

6. In a device of the class described, a trunk comprising a pair of easily separable sections, interlocking, reinforced ridges in the adjacent side edges of each of said trunk sections, a locking means for locking said trunk sections together comprising a plurality of bolt casings mounted on one of said trunk sections adjacent to said reinforced ridge portion, bolts reciprocally mounted in said casing apertures in said interlocked ridges of said trunk sections for receiving said bolts, a single bolt actuating means connected with each of said bolts, and means for rigidly securing said bolt actuating means against movement. 90

7. In a device of the class described, a trunk comprising a pair of easily separable sections, separable hinge means along the one edge of their adjacent sides, interlocking ridges along the remaining edges of their adjacent sides, a locking means for locking said trunk together comprising a plurality of bolt casings mounted one of said trunk sections adjacent to said reinforced ridge portion, bolts reciprocally mounted in said casing apertures in said interlocked ridges of said trunk sections for receiving said bolts, a single bolt actuating means connected with each of said bolts, and means for rigidly securing said bolt actuating means against movement. 100

8. In a device of the class described, a pair of self contained trunk sections, including hinged cover members and solid bottom members, and adapted to be secured with their bottom members together, interlocking channel members extending lengthwise with the one bottom edge of said sections forming readily separable hinge means, a tongue member on the opposite bottom edge of one of said sections, a channel member on the corresponding bottom edge of the other section adapted to receive said tongue member, and concealed locking means for securing said tongue and channel in locked relation. 110

9. In a device of the class described, a pair of self contained trunk sections, including hinged cover members and solid bottom members, and adapted to be positioned with their bottom members together, interlocking channel members extending lengthwise with the one bottom edge of said sections forming readily separable hinge means, a tongue member on the opposite bottom edge of one of said sections, a channel member on the corresponding bottom edge of the other section adapted to receive said tongue member, a plurality of reciprocally mounted bolts on the bottom of one section, apertures in said interlocking channel and tongue members for receiving said bolts, and actuating means for simultaneously reciprocating said bolts.

10. In a device of the class described, a pair of self contained trunk sections, readily separable hinge means on the one bottom edge of each section, interlocking tongue and channel means on the other bottom edges of said sections for preventing lateral and longitudinal displacement thereof and adapted to support said sections with their bottoms in spaced relation and locking means concealed between said bottoms for locking said sections together.

11. In testimony whereof, I have hereunto set my hand at San Diego, California, this 27th day of August, 1927.

ROY E. HARRIS.
